Patented Nov. 24, 1914.

UNITED STATES PATENT OFFICE.

ERNEST C. WEBSTER, OF EAST OAKLAND, CALIFORNIA, ASSIGNOR OF ONE-HALF TO
HENRY GRUENHAGEN, OF EAST OAKLAND, CALIFORNIA.

ELECTRIC WATER-HEATING FAUCET.

1,118,320.

Specification of Letters Patent.

Patented Nov. 24, 1914.

Application filed November 11, 1913. Serial No. 800,983.

To all whom it may concern:

Be it known that I, ERNEST C. WEBSTER, a citizen of the United States, residing at East Oakland, in the county of Alameda and State of California, have invented certain new and useful Improvements in Electric Water-Heating Faucets, of which the following is a specification.

My invention relates to devices for heating water and particularly to a faucet water heater.

The object of the invention is primarily the provision of a faucet adapted for use either as a wall or a basin faucet, so arranged that water may be heated just prior to its discharge from the faucet.

A further object of the invention is to provide a very simple means for electrically applying heat to water just before it issues from a faucet.

A further object of the invention is the provision of a faucet having an electrical water heater in conjunction therewith, the electrical heater being so arranged that the electricity does not require to be turned on by means of a switch in order to set the faucet in operation.

A further object of the invention is to provide a faucet of the character above stated so constructed that cold water may be allowed to issue therefrom, and provide it with a valve whereby the water instead of issuing directly from the faucet may be caused to traverse an electrical field and thereby be heated before its issuance from the faucet.

A further object is the provision of a faucet so constructed with a chamber inclosing an electrical heating appliance and provided with means whereby water may be directed either directly from the faucet or caused to circulate around the heating appliance, and further provided with means whereby the area around the heating appliance may be drained.

Other objects will appear in the course of the following description.

My invention is illustrated in the accompanying drawings wherein:

Fig. 1 is a side elevation of a faucet constructed in accordance with my invention, the upper portion of the faucet being broken away. Fig. 2 is a section on the line 2-2 of Fig. 1. Fig. 3 is a section on the line 3-3 of Fig. 1. Fig. 4 is a section on

the line 4-4 of Fig. 1. Fig. 5 is a fragmentary vertical section showing the valves or cocks turned to a closed position.

Corresponding and like parts are referred to in the following description and indicated in all the views of the accompanying drawings by the same reference characters.

Referring to these drawings, it will be seen that my improved faucet comprises an outer casting or shell designated generally 2, this shell comprising a base 3, a vertically disposed barrel 4 and a discharge pipe 5 which extends from the junction of the barrel 4 with the base 3.

Formed integral with the body of the faucet is an interior core 6 which is formed to provide a seat for the electrodes as hereafter described, and which is also formed at its rear with a vertically extending duct 7, this duct opening at its lower end upon the bottom of the base and extending upward through the faucet to the upper end of the barrel 4. The upper end of the barrel 4 is closed by a cap 8 which is screw threaded upon the barrel so that it may be readily removed.

The upper face of the core 6 forward of the duct 7 is formed with a seat 9 having downwardly and centrally converging side walls upon which there rests a block 10 of insulating material, this block being formed with a plurality of longitudinally extending passages 11 opening upon the base of the block. When the block 10 rests upon the seat 9 the central portion of the block inward of these passages is supported above the bottom of the seat as illustrated in Fig. 1.

Resting upon the central portion of the insulating block 10 is a cylindrical electrode 12, and disposed concentrically to this electrode 12 is a tubular electrode 13 whose lower end rests upon the margin of the block 10, the two electrodes being spaced from each other so as to leave a cylindrical space 14. The upper end of this tubular electrode is provided with radially extending perforations 15 opening into the space between the tubular electrode and the barrel.

Resting upon the upper ends of the electrodes 12 and 13 is a spacing and clamping block designated 16. This block is of insulating material. The block is reduced so as to fit within the upper end of the water chamber formed forward of the duct 7 and the center of the block is recessed to form a

socket 17 in which the upper end of the electrode 12 fits. The block is also annularly recessed as at 18 for the reception of the upper end of the tubular electrode 13. The block is formed with a wire passage 19 leading from the upper face of the block to the upper end of the socket 17.

Resting upon the upper face of the clamping block 16 is a complementary clamping block 21. The upper face of the block 16 and the lower face of the block 21 are formed with the complementary wire ducts 22 and 23 which open into the wire passage 7. The conducting wires for the electrodes pass up through the base of the faucet through the passage 7 into the upper end of the barrel and into the ducts 22 and 23 and thence down respectively through the passages 19 and 20 to the respective electrodes. The upper clamping block when forced down will hold these wires securely in place and the upper clamping block is held down upon the lower clamping block by the cap 8. When this cap is screwed down upon the barrel it will hold the clamping blocks in firm engagement with the wires.

For the purpose of controlling the flow of water, the core 6 is provided with two transversely extending tapered cylindrical valve chambers 24 and 25. The valve chamber 25 intersects a duct 26 leading from the main water duct 27 which extends down through the base of the faucet while the valve chamber 24 is disposed between the upper end of the water duct 27 and the seat 9 and intersects a passage leading from the seat 9 to the upper end of the duct 27. A passage 28 leads off at right angles from this last named duct and discharges into the water chamber of the faucet immediately in front of the core.

Disposed within the valve chamber 25 is the tapered rotary valve 29 having a passageway extending diametrically through it, while disposed in the valve chamber 24 is the rotary cock or valve 30 which has a passageway extending diametrically through it and one in quartering relation to the first named passage. In other words, this is a three-way cock. Each of these cocks or valves is provided with a handle whereby it may be rotated. When the cocks are in the position shown in Fig. 5, the passage of water from the duct 27 out of the faucet is entirely prevented. In other words, the faucet is turned off. When the cock 29 is given a quarter turn in a counterclockwise direction from the position shown in Fig. 5, water is permitted to flow from the duct 27 directly outward into the discharge pipe 5. When the cock 29 is turned to the position shown in Fig. 1 and the cock 30 is turned to the position shown in the same figure, then communication is established between the duct 27 and the space between the elec-

trodes and water will pass upward between the electrodes and out through the perforations 15, thence down the outside of the electrodes and through the discharge pipe 5.

While I have illustrated the faucet as being provided with a base 3 in alignment with the barrel 4, it will be understood that this base might be disposed at right angles to the barrel 4 as shown in dotted lines in Fig. 1. In the first case, the faucet is adapted to be used as a basin while in the second case the faucet is adapted to be attached to a wall. This change in the direction of the base will not affect in any way the operation of the faucet.

The operation of the faucet will be obvious from what has gone before. Normally both of the cocks 28 and 29 are turned off. If it is desired that cold water shall issue from the faucet, the cock 29 is turned so as to establish communication between the discharge pipe and the duct 27. If it is desired that hot water shall issue from the faucet, the cock 29 is turned to its closed position and the cock 30 turned so as to establish communication between the upper end of the duct 27 and the space between the electrodes. Water will then rise upward, pass around between the electrodes, establishing electrical connection between the electrodes and water will flow out through the perforations 15 and down around the electrodes and pass out through the discharge pipe. In its passage this water will be heated by the heating of the electrodes due to the passage of the current between the electrodes. When the cock 30 is turned to cut off a supply of water to the electrodes, the drain duct will be turned so as to communicate with the space in front of the core and thus any water which may be contained in the space between the electrodes below the perforations 15 will be drained off.

It will be seen that when the faucet is connected for daily use, the electric current as well as the water itself is under the entire control of the faucet cocks, no electric switches or water valves being required. It will be seen that the heating element consisting of the two electrodes may be easily removed from the interior of the faucet or replaced therein and that thus the faucet can be readily cleaned and that the wires leading to these electrodes may be easily put into position and easily connected or disconnected. Preferably the electrodes are of carbon so as not to contaminate the water or cause an electrolytic action. It will also be noticed that not only is my faucet adapted for furnishing either cold water or hot water, but that by properly turning the cocks 29 and 30, a portion of cold water and a portion of hot water may be discharged through the discharge nozzle 5. It is further to be noticed that for the purpose of

holding the supporting block 10 to the electrodes to permit the simultaneous removal of the electrodes and the supporting member 10, I provide tubular sleeves 10* which extend up from the perforations 11 of the block 10 and into the space between the electrodes, thus spacing them from each other at their lower ends and connecting the electrodes to the supporting member 10.

10. While I have illustrated these electrodes, one as a rod having a cylindrical cross section and the other as being a tube extending entirely around the rod, I wish it distinctly understood that I might form these 15 electrodes in other shapes and that the outer electrode of the heating element need not be annular in cross section but might only extend a portion of a circle.

What I claim is:

20. 1. The combination with a faucet having a chamber, an electrically energized heating element therein, said element comprising electrodes connected in an interrupted circuit and spaced from each other, means for directing water into said chamber or cutting off the supply of water thereto, and means for draining the water from said chamber.

2. The combination with a faucet having a heating chamber formed therewith, of spaced electrodes extending upward within the heating chamber and connected in an interrupted circuit with a source of energy, and means for directing water into said heating chamber or cutting off the supply of water thereto and draining the space between said electrodes.

3. The combination with a faucet having a heating chamber formed therewith, of a heating element disposed in said chamber 40 and comprising concentrically arranged electrodes spaced from each other and adapted to be electrically energized when water passes into the chamber, and means for directing water into the chamber or cutting off the supply thereto and draining the space between said concentric electrodes.

4. The combination with a faucet having a vertically disposed heating chamber, the faucet having a discharge outlet communicating with the heating chamber and having passages in its base leading one directly to the discharge outlet and the other leading upward into said heating chamber, of an electrically energized heating element in the heating chamber comprising spaced electrodes adapted to be electrically connected by the presence of water in the heating chamber, and cocks disposed in the faucet and controlling the passage of water 55 through the passages in the faucet, one of said cocks being provided with a drainage passage leading from the space between said electrodes when the cock is turned to cut off the flow of water to the heating chamber.

5. The combination with a faucet having

a vertically disposed heating chamber, the faucet having a discharge outlet communicating with the heating chamber and having an inlet passage in its base and separate passages leading one into the heating chamber 70 and the other directly to the discharge outlet, of an electrically energized heating element in the heating chamber, and single means for connecting the supply passage of the faucet with the heating chamber or cutting off said connection and connecting the lower end of the heating chamber with the passage leading directly into the discharge outlet.

6. In a faucet of the character described, 80 a vertically disposed heating chamber, the faucet having a discharge outlet communicating with the upper end of the heating chamber and having an inlet passage in its base, a passage leading directly to the lower 85 end of the heating chamber and a passage in quartering relation to the first named passage and leading directly to the discharge outlet, and a rotatable valve disposed within the base of the faucet below the heating 90 chamber, said valve having intersecting passages at right angles to each other adapted to register with the passages before referred to thereby establish communication through said passages or disestablish said 95 communication.

7. A faucet of the character described, a heating chamber having a discharge outlet at its lower end, a cap closing the upper end of the heating chamber, a heating element 100 disposed within the heating chamber and comprising spaced electrodes, one of said electrodes surrounding the other and said last named electrode being provided with perforations at its upper end leading into 105 said chamber, non-conducting supports spacing said electrodes, said cap engaging one of said supports and holding the supports and the electrodes in position, and means for admitting water into the space between said 110 electrodes at the lower end thereof.

8. A faucet of the character described, a heating chamber having a discharge outlet at its lower end, a cap closing the upper end of the heating chamber, a heating element 115 disposed within the heating chamber and comprising spaced electrodes, one of said electrodes surrounding the other and said last named electrode being provided with perforations at its upper end leading into 120 said chamber, non-conducting supports spacing said electrodes, said cap engaging one of said supports and holding the supports and the electrodes in position, and means for admitting water into the space between said 125 electrodes at the lower end thereof and draining said space.

9. In a faucet of the character described, a faucet body embodying a chamber, a base, a discharge outlet and a core formed with 130

- the body at the base of the heating chamber, said core having a supply duct, a passage leading therefrom laterally through the core and opening opposite the discharge outlet 5 and a passage leading to the upper face of the core, an electrically energized heating element disposed in said chamber and comprising two spaced electrodes supported upon the upper face of the core, one of said electrodes 10 surrounding the other of the electrodes and having a water outlet at its upper end, a cock extending through the faucet and the core and controlling the first named passage, and a cock extending through the 15 faucet and core and controlling the second named passage, said cock having a drainage passage.
10. In a faucet of the character described, a faucet body embodying a base, a chamber 20 and a discharge outlet disposed at the lower end of the base, and a core formed with the body at the base of the heating chamber, said core having a supply duct, a passage leading therefrom laterally through the core 25 and discharging opposite the discharge outlet and a passage leading to the upper face of the core, said upper face being formed with an annular seat, an insulating block disposed upon the upper seat and having a plurality of upwardly extending passages 30 communicating with the under face of the block, the heating element comprising outer and inner spaced electrodes supported upon said block, the space between said electrodes 35 registering with said passages in the block, a block of insulating material resting upon and spacing the upper ends of the electrodes, a cap detachably closing the upper end of
- the chamber and bearing upon said upper block, electrical connections passing through 40 said upper block and engaging with said electrodes, and independent means for controlling the first and second named passages through said core.
11. In a faucet of the character described, 45 a heating chamber, a heating element in said chamber comprising spaced electrodes, upper and lower clamping members engaging and supporting the upper ends of the electrodes, the confronting faces of the clamping members having conductor receiving recesses formed therein, and a cap having screw threaded engagement with the upper end of the heating chamber and engaging the upper 50 one of said clamping members.
12. In a faucet of the character described, a heating chamber, a cap for closing the latter, spaced electrodes in the heating chamber, a removable insulating member for supporting the lower ends of the electrodes, an insulating member engaging with and supporting the upper ends of the electrodes and having wire receiving ducts leading therethrough whereby electric wires may be connected to the electrodes, said faucet being formed within the chamber with a wire duct extending longitudinally of the chamber opening into the upper portion of the chamber immediately below said cap.
- In testimony whereof I affix my signature in presence of two witnesses.
